(57) **CLAIM**

The ornamental design for a stork picture frame, as shown and described.

DESCRIPTION

FIG. 1 is a perspective view of a stork picture frame in accordance with the present design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The evenly broken lines represent parts of the article that form no part of the claimed design. The smaller broken lines shown in FIGS. 1 and 2 represent an internet web address that forms no part of the claim.

The solid black surface appearance of the eye features depicts the color black included in the claimed design.

1 Claim, 5 Drawing Sheets
